UNITED STATES PATENT OFFICE.

DAVID C. TWEDELL, OF PHOENIX, ARIZONA, ASSIGNOR OF ONE-HALF TO JOHN J. KOLBERG, OF PHOENIX, ARIZONA.

SAFETY-PIN.

1,197,972.

Specification of Letters Patent. Patented Sept. 12, 1916.

Application filed April 26, 1916. Serial No. 93,617.

To all whom it may concern:

Be it known that I, DAVID C. TWEDELL, a citizen of the United States, residing at Phoenix, in the county of Maricopa and State of Arizona, have invented certain new and useful Improvements in Safety-Pins, of which the following is a specification.

This invention relates to certain new and useful improvements in safety pins of that class provided with a shield or the like whereby it is adapted for use in laundry work, in rough-dry work and wet wash, for tagging socks and, in fact, any and every use to which a pin of this character could be put in a laundry to save the expense of marking, as well as all other uses for which it is adapted.

The present invention has for its objects among others to provide a simple and cheap safety pin of this general character which will not catch on objects it comes in contact with, such as hooks and eyes on clothing, and yet which will be sufficiently strong to withstand all the strain to which it may be put and not be twisted out of shape by the weight of the wet clothing or hard usage.

The pin may be constructed in any shape to meet the requirements and can be numbered or lettered in any manner as necessitated by the use to which it is to be put in the laundry or other trade and the guard and shield are so constructed and arranged that it is impossible for the pin to become accidentally removed, but yet permitting it to be removed with ease and safety when desired. It is equally as well adapted for household use and may be made as fanciful as may be desired.

Other objects and advantages of the invention will hereinafter appear and the novel features thereof will be pointed out in the appended claims.

The invention is clearly illustrated in the accompanying drawings, which, with the numerals of reference marked thereon, form a part of this specification, and in which—

Figure 1 is a face view of my improved safety pin. Fig. 2 is an edge view thereof. Fig. 3 is an end view with the guard in closed position. Fig. 4 is a view of the blank from which the guard, shield and tongue are formed. Fig. 5 is an end view showing the manner of releasing the pin point.

Like numerals of reference indicate like parts throughout the several views.

Referring to the drawings, 1 designates a pin of wire of any well-known form adapted for the purpose having a pointed end 2, as usual, the other end being bent at an angle, as at 3, to enter a hole 4 in the shield so that when it is in place and the blank from which the shield and guard are formed is pressed together it will be rigidly held in place.

The shield and guard may be formed of any suitable material, but preferably of a single piece of thin flat spring material, such as shown at 5 in Fig. 4. This material is bent along the line 6 to form the tongue 7, the bend being preferably rounded, as shown in Fig. 3, and along the line 8 to form the guard member 9. The hole 4 which receives the right-angled end of the fixed arm of the pin is adjacent the folding line 9. In practice, the end of the fixed member of the pin 1 is inserted in the hole 4, the blank is bent over the same and the adjacent portion of the fixed member of the pin and pressed together, being soldered, if necessary, or otherwise fixedly held in position, and then the blank is bent along the line 6 forming the tongue 7 which overlaps the guard member 9, as seen clearly in Figs. 1 and 3.

The tongue 7 is normally bent outwardly at an angle from the shield portion 5 and the inherent resiliency of the guard member 9 normally causes the same to flex outwardly and engage the under surface of the guard, as seen in Fig. 3. The free end of the guard member is beveled upon the inner surface, as seen at 10, to prevent the pin from catching on the edge and possibly forcing itself out of the shield when any undue pressure is put upon it.

I may sometimes roll out the guard end from its point of connection with the shield member so as to make it more flexible, thus allowing me to make the shield of heavier material so that it will be stronger and yet preserve the requisite resiliency in the guard. The guard is preferably substantially the same width as the shield so as to make it more substantial and less liable to be twisted out of shape and at the same time insuring greatest strength.

In practice, after the pointed end of the pin has been forced through the material,

it is allowed to engage the guard 9 when the outward pressure on the pin caused by the coil 11 thereof will force the pin point in the direction of the arrow in Fig. 1 until it 5 passes the free edge of the guard, the pressure forcing the guard inward to permit of the passage of the pin beyond the free end of the guard, when the latter springs outward against the inner face of the tongue 10 and the pin point is forced outward into the position seen in Figs. 1 and 3, there to remain until it is intentionally released which may be done by placing the thumb of the left hand on the guard, as seen in Fig. 5, and 15 pressing it inward, when with the right hand the pin may be forced downward and outward by the free edge of the guard, as seen in Fig. 5, which makes the operation convenient and simple and one in which 20 there is no danger of sticking the thumb. As soon as the pin point has passed the free edge of the guard and pressure removed, the guard springs back into the position in which it is seen in Fig. 3, and the pin can be 25 again easily inserted between the guard and the tongue. It is to be noted in Fig. 3 that the free end of the tongue extends a sufficient distance beyond the free end of the guard to form a tapered entrance for the 30 pin to avoid all possibility of the guard forcing the tongue sufficiently outward to allow the pin to accidentally become disengaged.

Modifications in detail may be resorted to 35 without departing from the spirit of the invention or sacrificing any of its advantages.

What is claimed as new is:—

1. A safety pin having an integral shield, 40 guard, and tongue, the said guard being resilient and normally flexed outward and pressing against the inner face of the tongue, the tongue being of less length than the guard and extending at an angle from the shield and beyond the free end of the 45 guard.
2. A safety pin having an integral shield, 50 guard and tongue, the shield having opposite bends one of which embraces one end of the pin, the said guard being resilient

and normally flexed outward and pressing against the inner face of the tongue, the tongue being of less length than the guard and extending at an angle from the shield and beyond the free end of the guard, the 55 inner face of the free end of the guard being inwardly beveled.

3. A safety pin and a combined shield, 60 guard and tongue formed of a single piece of material bent upon itself to rigidly hold the fixed member of the pin, the guard being resilient and of greater length than the tongue, and the tongue extending at an angle from the shield and overlapping the 65 free end of the guard, the latter being normally flexed outwardly and bearing against the inner face of the tongue at a distance from the free end of the latter.

4. A safety pin and a combined shield, 70 guard and tongue formed of a single piece of material bent upon itself to rigidly hold the fixed member of the pin, the guard being resilient and of greater length than the tongue, and the tongue extending at an angle from the shield and overlapping the 75 free end of the guard, the latter being normally flexed outwardly and bearing against the inner face of the tongue at a distance from the free end of the latter; said shield, guard and tongue being all substantially the 80 same width.

5. As an improved article of manufacture, a shield for a safety pin formed of a single piece of material bent upon itself to embrace at one end one end of a pin and the other 85 end being bent back upon itself to form a tongue, and a guard extended from the first-named bend with its free end extended beyond and beneath the free end of the tongue and normally flexed outward toward said 90 tongue at an angle thereto, leaving a tapered entrance for the free end of the pin between the guard and tongue.

In testimony whereof I affix my signature in presence of two witnesses.

DAVID C. TWEDELL.
